FIG. 3

Fig. 8.

INVENTOR

HENRY T. BUSSMANN,

by *John W. Klemens*. ATTORNEY.

UNITED STATES PATENT OFFICE.

HENRY T. BUSSMANN, OF ST. LOUIS, MISSOURI.

CARTRIDGE FUSE.

Application filed May 7, 1919. Serial No. 295,377.

To all whom it may concern:

Be it known that I, HENRY T. BUSSMANN, a citizen of the United States, residing at St. Louis, in the State of Missouri, have invented certain new and useful Improvements in Cartridge Fuses, of which the following is a clear, full, and exact description, such as will enable others skilled in the art to make and use the same.

10 The object of my invention is to provide a fuse that possesses great mechanical strength to withstand heavy overloads and short circuits, and can be made at a low cost. These and other advantages of my 15 invention will be more readily understood by reference to the accompanying drawings.

Fig. 1 is a longitudinal view, with casing partly broken away. Fig. 2 is a longitudinal view at right angles to that shown 20 in Fig. 1. Fig. 3 is a perspective view of a terminal. Fig. 4 shows two fuse links attached to the terminal between which the pin is positioned. Fig. 5 shows a terminal end adapted to be held against sidewise 25 movement by the pin and Fig. 6 shows the terminal so formed that with the link attached, the pin serves to prevent sidewise movement of the terminal.

In the drawings, 4 is a fuse link attached 30 by means of bolt 5 or any other suitable means, to the terminal 6. 7 is a rivet passing through the tube for holding the cap 8 upon the casing 9. 10 is a stamping attached on the terminal 6.

35 The fuse strip 4 and the stamping 10 being located on opposite sides of the rivet 8, prevent sidewise movement of the terminal. Where two fuse links are used, one on each side of the terminal, the stamping 10 is

40 eliminated as in Fig. 4. Likewise, where only one link is used, the stamping 10 can be eliminated by forming the end of the terminal so that a portion thereof is on the side of the rivet opposite the side the fuse

45 link is attached as in Fig. 5, or the terminal may have its inside end shaped to conform to the shape of the rivet and overlap on both sides of the rivet as in Fig. 6 to prevent sidewise movement of the terminal.

50 A portion of the terminal 6 abuts on the rivet 7 preventing inward movement of the terminal relative to the cap, and the nut of

bolt 5, or the end of the fuse link 4 or stamping 10 closely abuts the inside of the cap preventing outward movement of the 55 terminal.

From this it will be seen that I have provided substantial means for holding the caps on the casing and for holding the terminals against any movement, and that I have accomplished this with a minimum number of parts. It is obvious that instead of the bolt 5, I may use a rivet or a projection for holding the fuse link to the terminal and that I may in that case provide projections 60 on the terminal or other means for holding the terminal against outward movement. It is also obvious that instead of the rivet 7, I may use a bolt passing through the casing, and in this way make the fuse of the 65 renewable type.

I claim as my invention:

1. In a fuse, a casing, a cap, a terminal, means for preventing the outward movement of the terminal, and a pin extending 75 through the casing and beside the terminal against which pin a portion of the terminal abuts to prevent inward movement of the terminal.

2. In a fuse, a casing, a cap, a terminal, 80 means for preventing the outward movement of the terminal, and a pin extending through the casing and adjacent to a terminal surface whereby the inward movement of the terminal is prevented. 85

3. In a fuse, a casing, a cap, a terminal, a pin extending through the casing in front of the inner end of the terminal whereby inward movement of the terminal is prevented. 90

4. In a fuse, a casing, a cap, a terminal, a pin extending through the casing adjacent to the terminal and co-acting means on the terminal for preventing the sidewise movement of the terminal. 95

5. In a fuse, a casing, a cap, a terminal, a pin extending through the casing in front of the inner end of the terminal whereby inward movement of the terminal is prevented and coacting means on the terminal 100 for preventing the sidewise movement of the terminal.

HENRY T. BUSSMANN.
